CLAIM

I claim the ornamental design for a lamb coat, as shown and described.

DESCRIPTION

FIG. 1 is a perspective view of a lamb coat, showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines showing a lamb in FIG. 1 are included for the purpose of illustrating the invention in use, and form no part of the claimed design.

Furthermore, the broken line showing of stitching is part of the claimed design.
